Primary Examiner — Eric Goodman(74) *Attorney, Agent, or Firm* — QuickPatents, Inc.; Kevin Prince(57) **CLAIM**

I claim the ornamental design for a sink strainer, as shown and described.

DESCRIPTION

FIG. 1 is a perspective view of a sink strainer, showing my new design;

FIG. 2 is a top plan view thereof;

FIG. 3 is a bottom plan view thereof; and,

FIG. 4 is a left-side elevational view thereof, the right-side elevational view, front elevational view, and rear elevational view all being a mirror image thereof.

1 Claim, 3 Drawing Sheets**FIG. 1**

FIG. 2

FIG. 3

FIG. 4
